PAUL H. CRAGO, OF WILKINSBURG, PENNSYLVANIA, ASSIGNOR TO CHEATHAM ELECTRIC SWITCHING DEVICE CO., OF LOUISVILLE, KENTUCKY.

AUTOMATIC ELECTRICALLY-OPERATED DERAIL

Application filed December 21, 1925. Serial No. 76,769.

The principal object of this invention is to electrically operate railway safety derails automatically. The invention embodies a definite time period before operating the derails to the straight line or reverse position after a car has passed a given point, and a predetermined automatic time interval in which to accomplish the operation of the derail mechanism. This operation is accomplished in the system hereinafter more fully described.

For a more detailed description of my invention, reference is made to the accompanying drawings forming a part hereof, in which—

Figure 1 is a circuit diagram representative of my improved system and a diagrammatic plan view illustrating the relative position of the tracks, switch points, and switch point operating device.

Fig. 2 is a side elevation of the delayed-release, quick-acting magnetic blowout relay employed in this system, shown partially in cross section.

Fig. 3 is a front elevation of Fig. 2.

Fig. 4 is a side elevation of the relay employed to produce the definite time period required before operating the derails to the straight line position.

Fig. 5 is a front elevation of Fig. 4.

Fig. 6 is a top view of Figs. 4 and 5, along the line 4—4.

My invention is intended primarily for use with vehicles which are operated by means of an overhead trolley wheel or current collector, although it may be operated by vehicles in which current is supplied thereto by other methods. The control system consists essentially of a plurality of trolley contactors mounted on a trolley wire, an electric track switch mechanism for operating the derail switch points to the reverse or closed position, and later for restoring them to the normal or open position, and an automatic relay control device operated from the transient impulses of the trolley contactor circuit which, after a predetermined time, affect an operation of the derail mechanism to the closed or reverse position. The trolley contactors for controlling the derail

control device, are of a suitable type mounted on the trolley wire, one being in advance and one in the rear of the derail, the contactor in advance controlling the closed or reverse position of the derail, while the contactor in the rear is employed to control the normal or open position of the derail. Another contactor, placed in advance of the contactor controlling the reverse derail position, is often highly desirable in operation. This contactor has the same function as the contactor placed in the rear of the derail.

A time element device is incorporated in the control, co-operating with the circuit controlling the derail mechanism to the closed or reverse position. The time period of this time element control being of such magnitude that a car approaching the derail and passing under the contactor in advance of the derail, must come to an absolute stop and wait a short interval before the derail closes to the reverse position; the advantage of such an arrangement being that a car will always be compelled to operate at low speeds, namely, starting speeds through dangerous sections, such as steam road intersections, highway intersections, hills, curves, and et cetera.

The time element control consists of a normally energized retarded release relay T and a normally energized vibrating reed type time element relay V. The vibrating relay is equipped with a rigid armature carrying a contact, and a secondary flexible member carrying weights, and also controlling a pair of flexible contacts, so arranged and disposed that it will oscillate for a predetermined time when the relay becomes deenergized, before the flexible member will be brought into continuous contact engagement.

In Fig. 1 the letter 4 represents a trolley wire or conductor. Positioned adjacent the trolley conductor, are trolley contactors 5^d, 3 and 5, provided with flexible contact strips which are parallel and insulated from the trolley conductor. Each of the flexible contact strips being so arranged and disposed that they will be electrically connected to the trolley conductor when the current collector 4^b engages them respectively.

I also employ an electrically operated track

switch mechanism provided with two solenoids TR and TN, each having a connection to the ground through the common conductor 2.

5 The solenoids are provided with a reciprocating plunger which is drawn inwardly when the solenoid TN is energized, and outwardly when the solenoid TR is energized. The plunger is connected to the switch point 10 by means of a connecting link.

I also employ an electrically operated, normally open magnetic blowout relay, provided with an operating coil R, and a switch arm 9^a, for controlling the circuit of the track switch 15 operating solenoid TR. One terminal of the coil R is connected by wires 3^a and 3^b to trolley contactor 3, and the other coil terminal is connected to a normally open back contact 7 of relay T by wire 7^a. The relay is also provided with two normally open front contacts 20 9 and 16. The normally open front contact 9, being connected to the track switch operating solenoid TR by wire 9^c. The other normal open front contact 16 being connected to the 25 operating coil V, of the vibrating time element relay, through wires 8^a and 8^c. The contact 9 controls a heavy current circuit, and for this reason is enclosed within a magnetic blowout, the structure of which is well known 30 to those skilled in the art.

I also employ another relay of the same nature previously described for controlling the operating circuit of the track switch operating solenoid TN. Both of the latter mentioned 35 relays are equipped with a retarded release time element which may be brought about by various well known constructed principles. In regard to such devices as a copper or brass slug or sleeve about the core of the coil of the relay, as indicated by c, c, or it may be brought about by the spacing of the armature with respect to the core, or a combination of these, or by a dash pot arrangement, et cetera.

40 The preliminary time element control consists of the normally energized vibrator relay as heretofore mentioned and a normally energized retarded release relay. The circuit is so arranged, that after the vibrating member of the vibrator relay is brought to rest, it closes a pair of contacts wherein the operating coil of the retarded release relay is de-energized. The de-energization of the operating coil of the retarded release relay and the 45 releasing of its armature governed the time element period of the vibrator relay. The retarded release relay is provided with an operating coil T and a copper slug c, c, of the same character as employed on the magnetic blowout relays to produce a time element release.

For a more detailed description of the magnetic blowout relays controlling the circuits of their respective track switch operating solenoids reference is made to Figs. 2 and 3. 50 The figures, as drawn, show the armature of

the relay in a raised or energized position. This is not the normal position of the armature, but is so shown to indicate the operating position of the relay. With reference to Fig. 2, the letter R corresponds to the operating coil of the relay as heretofore described, and c, c, represents the copper slug mentioned to produce the desired retardation. It is not necessary to dwell at any great length on the detail construction of this relay as the drawing well discloses its design and operating characteristics, however, each of the lettered or numbered parts will be explained. 9^f and 9^g represent the stationary pole faces of the relay. 9^a is the movable armature of the relay which carries 9^e, which is a non-magnetic contact arm carrying the contact 9^d, operating within the magnetic blowout 9B. 9^j is the blowout operating coil and its operation is well known to those familiar with the design of heavy current relays. 9^k represents the pole faces of the latter mentioned blowout coil. 9B is an arc chute or barrier, constructed of a suitable heat and dielectric insulating material. The numeral 9 indicates the stationary normally open front contact located within the magnetic blowout.

For a more detailed description of the vibrating reed time element relay, Figs. 4, 5 and 6 are referred to. The relay is shown in its de-energized position to show how the flexible controlling contacts are affected when the vibrating reed nears the end of its oscillating period. In Fig. 4, the numeral 2 represents the operating coil of the said relay. Positioned adjacent each end of the coil are the pole pieces of the magnetic circuit. The numeral 19 indicates the movable armature for controlling the vibrating reed V¹. When the armature 19 is in an attracted position it mechanically engages the vibrating reed V¹ and moves it into the position shown by the dot-dash line. As soon as the armature releases, the vibrating reed V¹ is correspondingly affected, and due to its characteristics, oscillates for a predetermined time before it comes to a rest as shown by the solid lines. The weights W fastened on the extreme end of the vibrating reed V¹ are employed to control the oscillating period of the vibrating reed V¹, when a small time is desired, the weights are removed and when a longer time period is required, additional weights are added. Located within the vibrating member V¹ is a flexible contact that engages the adjustable contact 11. The adjustable contact 11 is carried in a supporting bracket mounted and insulated on the upper pole face of the relay. Positioned adjacent this supporting bracket is an insulated front contact 8, and is engaged by the flexible contact mounted on the armature 19. A lengthy description of this relay is not made, as it is not a prime feature of this invention, but is disclosed so that those familiar in relay construction and design,

will be assisted in understanding the general operation of the circuit disclosed and described.

With reference to the system shown in Fig. 1, if the trolley wheel 4^b engages the trolley contactor 3, the operating coil V of the vibrator relay will be shunted and de-energized. Attention is called to the initial normally closed circuit of the operating coil V which is completed from the trolley conductor 4, through wire 4^a , wire 13, wire 14, armature 19 of the vibrator relay, front contact 8 of the vibrator relay, through wire 8^g , wire 8^h , operating coil V of the said relay, wire 18, resistor 3^e , resistor 6^a , to the ground 2^g . As a positive potential was applied to one terminal of coil V through wire 8^h , and the engagement of the trolley wheel 4^b with the trolley contactor 3 applied a like potential at the other terminal of the relay coil through wires 3^a , 3^b and 18, the operating coil V became de-energized, and its armature 19 was released and brought out of contact engagement with its front contact 8, wherein the circuit of the operating coil V was opened. Incident to this operation the vibrating member V^1 was released, and permitted to oscillate, making intermittent contact engagement with its back contact 11. Each of the contact impulses made by the contact engagement of the vibrating member V^1 and the back contact 11 tended to affect the operating coil T of the retarded release relay, but since contact impulses were of a short duration, the armature of the retarded release relay was not affected until the vibrating member V^1 came to rest, and into continuous contact engagement with the back contact 11. This operation resulted in the operating coil T, of the retarded release relay being shunted. The circuit for the normal energization of the coil T was completed from the trolley wire 4, through wire 4^a , wire 13, wire 14, wire 15, operating coil T of the retarded release relay, wire 11^c , resistor 11^d , to the ground 2^g . As one coil terminal of T ^{1} of operating coil T was connected to a positive source of energy normally, and the coil terminal T ^{2} became connected to a positive source of energy through the wire 11^a when the vibrating member V^1 came into continuous contact engagement with its back contact 11, the coil was shunted, and became de-energized, wherein its armature was released and brought into contact engagement with its normally open back contact 7. As soon as the armature T ^{a} was brought into contact engagement with its back contact 7, a circuit was established to energize the operating coil R of the magnetic blowout relay controlling the reverse switch operating magnet solenoid TR. This circuit being completed from the trolley conductor 4, through wire 4^a , wire 13, armature T ^{a} , back contact 7, wire 7^a , operating coil R of the said relay, wire 3^d , wire 3^b , resistor 3^e , resistor 6^a , to the ground

2 g . It will be noted, however, that as soon as the trolley wheel 4^b engaged the contactor 3, one coil terminal of the operating coil R was connected to a positive source of energy through wire 3^d , and since the other terminal was connected to a positive source of energy through the wire 7^a , as just described, no operation of the relay could be affected until a disengagement of the trolley wheel 4^b and trolley contactor 3 occurred. As soon as the operating coil R of the magnetic blowout relay became energized, its armature 9^a was brought into contact engagement with its normally open front contacts 9 and 16. The engagement with the front contact 9 resulted in a circuit being established to the reverse track switch operating solenoid TR, the circuit being completed from the trolley conductor 4, through wire 4^a , wire 12, armature 9^a , front contact 9, wire 9^c , solenoid TR of track switch operating mechanism, wire 2 to the ground 2^g . The establishment of this circuit resulted in the solenoid TR becoming energized and affecting an operation of the switch point to the reverse or straight line position. The contact engagement of the front contact 16 and the contact arm 9^a resulted in a circuit being established for the energization of the operating coil V, of the vibrating time element relay. This circuit being complete from the trolley conductor 4, through wire 4^a , wire 12, armature 9^a , front contact 16, wire 8^d , wire 8^e , wire 8^h , through the operating coil V, wire 18, resistor 3^e , resistor 6^a to the ground 2^g . As soon as the operating coil V became energized, its armature 19 was raised into contact engagement with its front contact 8 which in turn established a circuit for retaining the energization of the operating coil V as heretofore described. Incident to the raising of the armature 19, the vibrating reed V^1 was affected, and mechanically brought out of contact engagement with its back contact 11, removing the shunt that was applied to the operating coil T of the retarded release relay. The removing of this shunt permitted the operating coil T to become energized, wherein its armature T ^{a} was brought out of contact engagement with its back contact 7, and opened the circuit of the operating coil R, of the magnetic blowout relay. The operating of this circuit permitted the armature 9^a to release after the predetermined time, governed by the magnetic affect afforded by the copper slug c , c , as heretofore described. The releasing of the armature 9^a , the re-energization of the operating coil T, and the restoring of the vibrating member V^1 to its normal raised position, resulted in the relay's controlling the reversed track switch operating solenoid being restored to normal, and the switch point remaining in its reversed position.

As soon as the trolley wheel 4^b continued its course of travel and came into contact en-

gagement with the trolley contactor 5, the operating coil N of the magnetic blowout relay controlling the normal switch operating solenoid became energized. The circuit for this operation being completed from the trolley conductor 4, through the trolley wheel 4^b, through trolley contactor 5, wire 5^a, operating coil N of the said relay, wire 6, resistor 6^a to the ground 2^g. The energization of the coil N, as just described, resulted in the armature 10^a being raised into contact engagement with its respective front contacts 8^b and 10. The contact engagement of the armature 10^a and its front contact 10 resulted in a circuit being established to the track switch solenoid TN controlling the open position of the switch points. This circuit being established from the trolley conductor 4, through wire 4^a, armature 10^a, front contact 10, wire 10^a, solenoid TN, wire 2 to the ground 2^g. The energization of the solenoid TN resulted in the switch point being restored to its normal open position. An auxiliary contact 8^b is included on the relay for the purpose of insuring the operating coil V being energized and retaining its armature in the raised position. This is very desirable as it is quite possible in this system that through an intermittent failure in the source of power, which is a frequent occurrence in railway systems, to permit the armature V to remain in a de-energized position. Attention is called to the possible addition and location of the auxiliary restoring contactor 5^a which is placed in advance of the derail operating system. The purpose of this contactor being to insure the derail being in an open position when the car approaches the derail switch points.

To sum up the operation of the system, a car on the approach of the derail passes under the trolley contactor 5^a, wherein a control is affected to insure the derail switch points being in an open position. As a car approaches and goes under the trolley contactor 5, it operates a control which, after a predetermined time, automatically effects an operation of a relay system to effect an operation of the derail switch points to the closed or reverse position. As soon as the car proceeds and passes under the trolley contactor 5 it operates a control for restoring the derail to its normal open position.

There are, of course, modifications and arrangements of parts which may be made from those shown in the above disclosure, and which still fall within the scope of my invention.

I claim:

1. In an automatic electrically operated derail system, the combination of an electrically operated derail throwing device, a relay control and controlling elements, co-operative means therewith that when one of the controlling elements is engaged, a relay con-

trol will be affected to operate the derail to the closed position after a predetermined time interval.

2. In an automatic electrically operated derail system, the combination of an electrically operated derail throwing device, a relay control and controlling elements, co-operative means therewith that when one of the controlling elements is engaged, a relay control will be affected to operate the derail to the closed position after a predetermined time interval, and only after disengagement of the said controlling elements.

3. In an electric derail operating device, the combination with a track solenoid, trolley conductor and trolley contactor, of a normally open circuit connecting the trolley conductor and track solenoid, a circuit closing means therein, of means controlled by contact of a trolley with a trolley contactor, for operating an electrically controlled time element device controlling means to permit the operation of the circuit closing means after a predetermined time interval and only upon disengagement of the trolley conductor and trolley contactor.

4. In an electric derail operating device, the combination with a track solenoid, trolley conductor and trolley contactor, of a normally open circuit connecting the trolley conductor and track solenoid, a circuit closing means therein, of means controlled by contact of a trolley with a trolley contactor for operating a normally energized time element device controlling means to permit the operation of the circuit closing means after a predetermined time interval and only upon disengagement of the trolley conductor and trolley contactor.

5. In an electric derail operating device, the combination with a track solenoid, trolley conductor and trolley contactor, of a normally open circuit connecting the trolley conductor and track solenoid, a circuit closing means therein, of means controlled by contact of the trolley conductor with the trolley contactor for operating an electrically controlled time element device, permitting the operation of the circuit closing means, for a predetermined time, after a predetermined time interval, and only upon disengagement of the trolley conductor and trolley contactor.

6. In an electric derail operating device, the combination with a track solenoid, trolley conductor and trolley contactor, of a normally open circuit connecting the trolley conductor and track solenoid, a circuit closing means therein, of means controlled by the contact engagement of a traveling contact member of an electric car and the trolley contactor, for controlling a normally energized time element device that must function before the circuit closing means can affect an operation of the derail to the closed position.

7. In an electric derail operating device,

the combination with a track solenoid, trolley conductor and trolley contactor, of a normally open circuit connecting the trolley conductor and track solenoid, a circuit closing means therein, of means controlled by the contact engagement of the trolley conductor and trolley contactor, for controlling the circuit of a normally energized time element device, permitting the operation of the circuit closing means for a predetermined time after a predetermined time interval, and only upon disengagement of the trolley conductor and trolley contactor, and render the circuit closing means inoperative while engaged.

8. In an electric derail operating device, the combination with a track solenoid, trolley conductor and trolley contactor, of a normally open circuit connecting the trolley conductor and track solenoid, a circuit closing means therein, of means controlled by the contact engagement of the trolley conductor and trolley contactor, for controlling the circuit of a normally energized time element device, permitting the operation of the circuit closing means for a predetermined time after a predetermined time interval, and only upon disengagement of the trolley conductor and trolley contactor, and means provided for restoring the said time element device to normal.

9. In an electric derail operating device, the combination with a track solenoid, trolley conductor and trolley contactor, of a normally open circuit connecting the trolley conductor and track solenoid, a circuit closing means therein, of means controlled by the contact engagement of the trolley conductor and trolley contactor for shunting the circuit of a normally energized time element device, permitting the operation of the circuit closing means after a predetermined time, and only upon disengagement of the trolley conductor and trolley contactor, and means for retaining the said time element device in an operative state until the circuit closing means has operated.

10. In an electric derail operating device, the combination with a track solenoid, trolley conductor and trolley contactor, of a normally open circuit connecting the trolley conductor and track solenoid, a circuit closing means therein, of means controlled by the contact engagement of the trolley conductor and trolley contactor, for shunting the circuit of a normally energized time element device, permitting the operation of the circuit closing means after a predetermined time, and only upon disengagement of the trolley conductor and trolley contactor, and means for retaining the said time element device de-energized until the circuit closing means has operated.

11. In an electric derail operating device, the combination with a track solenoid, trolley conductor and trolley contactor, of a nor-

mally open circuit connecting the trolley conductor and track solenoid, a circuit closing means therein, a trolley contactor control, means affected by the trolley contactor control, which, after a predetermined time operates to control the circuit closing means after disengagement of the trolley conductor and trolley contactor.

12. In an electric derail operating device, the combination with a track solenoid, trolley conductor and trolley contactor, of a normally open circuit connecting the trolley conductor and track solenoid, a circuit closing means therein, a trolley contactor control, means affected by the trolley contactor control, which after a predetermined time, operates to control the circuit closing means for a predetermined time, after disengagement of the trolley conductor and trolley contactor.

13. In an electric derail operating device, the combination with a track solenoid, trolley conductor and trolley contactor, of a normally open circuit connecting the trolley conductor and track solenoid, a circuit closing means therein, a trolley contactor control, means affected by the trolley contactor control, which after a predetermined time, operates to control the circuit closing means for a predetermined time incident to the operation of a plurality of solenoids, and after disengagement of the trolley conductor and trolley contactor.

14. In an electric derail operating device, the combination with a track solenoid, trolley conductor and trolley contactor, of a normally open circuit connecting the trolley conductor and track solenoid, a circuit closing means therein, a trolley contactor control, means affected by the trolley contactor control, which after a predetermined time, operates to control the circuit closing means for a predetermined time, after disengagement of the trolley conductor and trolley contactor, wherein the relay system is restored to a normal condition.

15. In an electric derail operating device, the combination with a track solenoid, trolley conductor and trolley contactor, of a normally open circuit connecting the trolley conductor and track solenoid, a circuit closing means therein, a current collector to engage the trolley contactor, of means controlled by contact engagement of the current collector and trolley contactor for controlling the circuit of an electric time element device, that must function before the circuit closing means can operate upon disengagement of the current collector and trolley contactor, regardless of the position of the current collector.

16. In an electric derail operating device, the combination with a track solenoid, trolley conductor and contactor, of a normally open circuit connecting the trolley conductor and track solenoid, a circuit closing means there-

in, of means controlled by contact engagement of the trolley conductor and trolley contactor for controlling the circuit of a normally energized time element device, permitting the operation of a relay after a predetermined time to thereby control the circuit closing means, only after disengagement of the trolley conductor and trolley contactor.

17. In an electrically operated derail, the combination with a track solenoid, trolley conductor and trolley contactor, of a normally open circuit connecting the trolley conductor and track solenoid, a circuit closing means therein, a normally energized time element device co-operating therewith, a current collector to engage the trolley contactor, of means controlled by contact engagement of the current collector and trolley contactor, for controlling the circuit of the said normally energized time element device, a shunt provided by the contact engagement of the current collector and trolley contactor, preventing the operation of the relay controlling the circuit closing means until disengagement of the current collector and trolley contactor, wherein the circuit closing means is operative and a source of power is provided to restore the time element device to normal.

18. In an electric derail operating device, the combination with a track solenoid, trolley conductor and trolley contactor, of a normally open circuit connecting the trolley conductor and track solenoid, a trolley contactor control, a time element relay affected by the trolley contactor control, said relay operable after a predetermined time interval to control a second relay, to close the said normal open circuit connecting the trolley conductor and track solenoid.

19. In an electric derail operating device, the combination with a track solenoid, trolley conductor and trolley contactor, of a normally open circuit connecting the trolley conductor and track solenoid, a trolley contactor control, a time element relay affected by the trolley contactor control, said relay to be shunted after a predetermined time interval to affect a second normally open retarded release relay, the latter to close the normal open circuit connecting the trolley conductor and track solenoid.

20. In an electric derail operating device, the combination with a track solenoid, trolley conductor and trolley contactor, of a normally open circuit connecting the trolley conductor and track solenoid, a circuit closing means therein, a trolley contactor control, a time element relay arranged to be shunted by the said trolley contactor control, said relay to affect after a predetermined time interval the said circuit closing means.

21. In an electric derail operating device, the combination with a track solenoid, trolley conductor and trolley contactor, of a nor-

70 mally open circuit connecting the trolley conductor and track solenoid, a circuit closing means therein, a normally energized time element relay arranged to be controlled by the said trolley contactor, said relay to shunt, after a predetermined time interval, a second retarded release relay, the latter to close a circuit to operate the circuit closing means only upon disengagement of the trolley and trolley contactor.

75 22. In an electric derail operating device, the combination with a track solenoid, trolley conductor and trolley contactor, of a normally open circuit connecting the trolley conductor and track solenoid, a circuit closing means therein, a normally energized time element relay arranged to be controlled by the said trolley contactor, said relay to shunt after a predetermined time a second retarded release relay, the latter to close a circuit to operate the circuit closing means only upon disengagement of the trolley and trolley contactor; wherein a source of power is supplied to restore the relay system to a normal operating condition.

80 In testimony whereof I affix my signature.

PAUL H. CRAGO.
